J. L. Hill,

Attorney
Elmore Talbert

UNITED STATES PATENT OFFICE.

JOHN L. HILL, OF SEATTLE, WASHINGTON.

VEHICLE-SPRING.

1,322,440.

Specification of Letters Patent. Patented Nov. 18, 1919.

Application filed January 24, 1919. Serial No. 272,894.

To all whom it may concern:

Be it known that I, JOHN L. HILL, a citizen of the United States, residing at Seattle, in the county of King and State of Washington, have invented new and useful Improvements in Vehicle-Springs, of which the following is a specification.

This invention has reference generally to improvements in that class of inventions known as springs, braces and equalizers and more particularly relates to an improved vehicle spring.

The present invention has for its primary aim and object to provide a device of the above mentioned character wherein the leaves of the spring are of an improved construction and are designed so as to be operatively connected together in such a manner as to obviate leaf binding and to prevent squeaking, etc., when the parts are in an assembled position.

More particularly this invention embraces the provision of a device of the above mentioned character wherein the fastening means for the leaves at the centers thereof is designed to embrace the enlarged central portions of the leaves and to embrace the spacing or filler blocks so as to prevent relative movement of the spring and filler blocks and to also operatively connect the spring to the axle.

It is a more specific object of the present invention to provide a spring of the above mentioned character wherein clips of the improved construction are employed for slidably accommodating the ends of the leaves and for accommodating and retaining spacing or filler blocks against displacement, said clips acting in conjunction with the hangers for insuring of an effective connection between the spring and the vehicle chassis.

Among the other aims and objects of this invention may be recited the provision of a device of the character described with a view to compactness, and in which the number of parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings form-

ing a part hereof, and wherein is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings, in which:

Figure 1 is a side elevation of the spring attached.

Fig. 2 is a longitudinal central sectional view thereof.

Fig. 3 is a top plan view of one of the leaves.

Fig. 4 is a top plan view of one of the central spacing or filler blocks.

Fig. 5 is a horizontal sectional view through the clip, and

Fig. 6 is a perspective detail of one of the clips.

Fig. 7 is a perspective view of one of the end spacer or filler blocks.

Similar characters of reference are employed in all of the above described views, to indicate corresponding parts.

Referring now, more particularly, to the accompanying drawings, there is provided a plurality of leaves 1 having enlarged rectangular central portions 2 while the side portions taper as at 3 toward the outer ends. Substantially rectangular spacing or filler blocks 4 are now employed and are disposed transversely of the enlarged central portions 2 and have their corners recessed inwardly as at 5 to aline with the correspondingly recessed corners 6 of the enlarged portions 2, while straddled about the respective ends of the filler or spacing blocks 4 and the enlarged portions 2 and engaging the recessed portions 5 and 6 respectively thereof are U-bolts 7 the intermediate portions 8 of which first embrace the axle 9 while the upper ends are passed through openings in a rectangular retaining plate 10 and have the free threaded terminals engaged by nuts 11 which serve to clamp the parts in the position shown and described, the blocks, of course, serving to hold the side portions of the leaves in spaced relation with each other to obviate binding and squeaking noises while weakening of the spring is obviated due to the fact that no openings are formed through the central portion thereof.

110

In operatively connecting the leaves 1 together there are employed improved clips generally designated by the numeral 12. Each clip is substantially rectangular in cross section and consists of a base 13, spaced side walls 14 which rise from the side edges of the base and are inclined slightly toward each other and toward the rear wall 15 with which they are cast. The front of each clip 10 is open while extending inwardly from the forward edges of the side walls are vertically disposed and opposed flanges 16. A cover plate 17 is detachably secured to the upper edges of the side and rear walls by 15 means of suitable fasteners such as screws 18. An ear 19 is cast with and depending from the under surface of the base for a purpose that will presently appear. The small outer ends of the springs are slid between 20 the flanges and arranged within the adjacent clip while interposed between the springs are substantially rectangular filler blocks 20 the side edges of which taper as at 21 toward the rear edge, said plates being 25 inserted through the open top of the clip and of course being arranged alternately with respect to the ends of the springs. Subsequent to the arranging of the ends of 30 the springs and the blocks in the clip the cover 18 is attached while the ends of the springs have a slight sliding movement yet the blocks 20 are prevented from displacement owing to the retaining flanges 16. Hangers 22 are now employed and are pivotally suspended in opposed relation from 35 the chassis 23 of the vehicle by means of a pintle 24 and have their lower looped ends 25 pivotally connected on the opposite sides of the ear 19 by means of another pintle 26, 40 this arrangement serving to operatively connect the ends of the spring to the vehicle chassis, as is apparent. It will also be seen that by the provision of this peculiar construction leaf binding as well as squeaking 45 noises at the ends of the leaves is prevented and moreover the leaves are not weakened since no openings are provided therethrough for fastening the ends thereof together.

It is believed in view of the foregoing description that a further detailed description of the operation of the invention is entirely unnecessary. Likewise it is believed that the advantages of the invention will be readily apparent.

55 As many changes could be made in the above construction and many apparently widely different embodiments of this inven-

tion could be made without departing from the scope thereof, it is intended that all matter contained in the above description or 60 shown in the accompanying drawings shall be interpreted as illustrative and not in a limited sense. It is also to be understood that the language used in the following 65 claims is intended to cover all the generic and specific features of the invention herein described and all statements of the scope of the invention which as a matter of language might be said to fall therebetween.

What is claimed is:

70 1. A device of the character described comprising a plurality of leaves formed with enlarged central portions and tapered toward their respective ends, filler blocks disposed transversely of the leaves and alining 75 with the enlarged central portions thereof, fastening means for embracing the enlarged central portions of the leaves and the blocks for holding the leaves and blocks together and for connecting the spring to the axle of a vehicle, clips in which the ends of the leaves are slidably disposed, filler blocks disposed in the clips and retained thereby and interposed between the ends of the leaves, and means for pivotally suspending 80 the clips so as to support the ends of the spring.

2. A device of the character described comprising a plurality of resilient leaves formed with enlarged rectangular central 90 portions having the corners recessed, a plurality of filler blocks interposed between the leaves and positioned transversely thereof and alining with the enlarged central portions of the leaves and further having their 95 corners recessed, U-bolts for connecting the spring to the axle and for embracing the central portions of the leaves and the filler blocks, means coöperating with the bolts for retaining the bolts in position and for holding the leaves and filler blocks together, clips having the front faces open and formed with inturned flanges, the ends of the leaves being slidably accommodated in the clips, filler blocks disposed in the clips 100 and interposed between the ends of the leaves and prevented from displacement by the flanges, covers on the clips for retaining the parts therein, and pivotally mounted hangers for pivotally suspending the clips 110 and consequently supporting the spring.

In testimony whereof I affix my signature:

JOHN L. HILL.
